UNITED STATES PATENT OFFICE

GEORGE LASKER, OF CHICAGO, ILLINOIS

STEAM BOILER

Application filed July 9, 1923. Serial No. 650,516.

My invention relates to improvements in water tube steam boilers, and has for one of its objects the provision of baffle means whereby the heated gases are directed over 5 the tubes in a predetermined path.

Another object of my invention is to provide a three-drum boiler, the drums so arranged that feed water may be admitted into one of the drums and kept out of circulation 10 until the entire path of the heated gases has travelled through the boiler, thereby permitting the use of foul feed water in the boiler, the solid matter of said foul feed water being precipitated within that part of the boiler 15 located farthest away from the extreme heat.

The invention has among its other objects the production of a device of the kind described which is simple, convenient, compact, durable, reliable, efficient and satisfactory for 20 use wherever found applicable.

Many other objects and advantages of the construction herein shown and described will be obvious to those skilled in the art from the disclosures herein given.

25 To this end my invention consists in the novel construction, arrangement and combination of parts herein shown and described, and more particularly pointed out in the claims.

30 The figure illustrates a vertical section taken through a boiler of my improved construction.

1 indicates the front wall of a boiler setting, 2 the rear wall, and 3 the vertical side walls 35 thereof. 4 indicates a bridge wall arranged intermediate the front and rear walls at the rear end of the grate 5. The customary fuel and ash doors and the like may be provided in the setting, as desired.

40 Within the enclosing walls of the setting are arranged a plurality of drums, 6 indicating a front drum arranged at the upper front end of the boiler and 7 and 8 a pair of rear drums, the former being located at the bottom 45 rear end of the boiler and the latter arranged above the drum 7 at the rear end of the boiler but at a level below the front drum 6. A pair of banks of tubes 9 and 10, respectively, connect the drums 6 and 7, and another bank 50 of tubes 11 connects the drums 8 and 6.

It will be noted that the adjacent banks of tubes are spaced apart a distance sufficient to permit the entrance of a person therebetween for the purpose of inspecting, cleaning, repairing, or otherwise. Doors or openings 12 are provided in the side walls of the setting to permit the entrance of a person therethrough into the space between the adjacent banks of tubes. At the rear of the setting intermediate the drums 7 and 8 is 55 arranged a stack or flue 13 from which the spent gases are discharged.

The feed water is introduced by a pipe 14 into the drum 8, said drum being arranged at the coolest part of the boiler so that the 60 solids contained in said feed water may precipitate slowly to the bottom of the drum and drain off, if desired, through the pipe 15.

In order to direct the heated gases arising from the fuel bed over the banks of tubes in 65 a predetermined path, suitable baffles are provided. The baffle 17 extends from the bridge wall 4 along the bottom of the tubes 9 toward the front of the boiler. The baffle 18 is arranged on the top of the bank of tubes 9, 70 extending from the front drum to adjacent the drum 7. The baffle 19 is arranged on top of the bank of tubes 10 and extends from the drum 7 to adjacent the front drum. The top wall 20 of the boiler setting forms substantially a baffle above the bank of tubes 11, the 75 heated gases passing through the boiler along the tubes in the direction indicated by the arrows in the drawing.

A drain 16 is shown for draining the drum 80 7 and a steam-discharge outlet 21 leads from the drum 6. A gauge 22 is arranged at the front of the boiler to indicate the level within the drum 6.

It is apparent that the gases arising from the fuel bed and travelling over the banks of tubes will decrease in volume as they move through the boiler, therefore, the number of tubes in the various banks have been so proportioned that there are more tubes in the bank nearest the greatest volume of gases than in those banks farther away therefrom; or, in other words, there are more tubes in the bank 9 than in the bank 10, and there 85 100

are more tubes in the bank 10 than in the bank 11.

The baffles are so arranged that the heated gases pass along the tubes in a direction reverse to that in which the greatest proportion of water flows in the tubes, as for example, in the lowest bank the path of the water will be from the drum 7 to the drum 6 and the gases will be in the opposite direction. In the bank of tubes 10, the greater proportion of the water will pass from the drum 6 to the drum 7 inasmuch as the lower ends of the tubes of the bank 10 are hotter than the upper ends, the gases passing along said bank in the reverse direction. The same is true of the bank of tubes 11. This greatly accelerates the flow of water in the tubes.

Inasmuch as the feed water drum 8 is located below the drum 6, the feed water is not brought into contact with the heated gases until they are ready to be discharged through the flue 13. This section of the boiler acts as an economizer directly connected and opening into the other drums and arranged so that substantially all of the solid matter in the water in the drum 8 will be precipitated to the bottom of said drum. The feed water from the drum 8 will flow from the drum 8 at the rate it is supplied thereto.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. In a device of the kind described and in combination, a boiler having a front drum, a pair of rear drums at different elevations below said front drum, said rear drums being spaced from each other to permit the passage of gases of combustion therebetween, banks of tubes directly connecting the front drum with the rear drums, means for introducing feed water into the upper of said rear drums, and baffles for directing the gases over said tubes and between said rear drums in a predetermined manner.

2. In a device of the kind described and in combination, a boiler having a front drum, a pair of rear drums at different elevations below said front drum, said rear drums being spaced from each other to permit the passage of gases of combustion therebetween, banks of tubes directly connecting the front drum with the rear drums, a flue intermediate said rear drums, means for introducing feed water into the upper of said rear drums, and baffles for directing the gases over said tubes in a predetermined manner and into said flue so that said gases contact with the top bank of

said upper drum just prior to their discharge through the said flue.

3. In a device of the kind described and in combination, a boiler having a front drum, a pair of rear drums at different elevations below said front drum, said rear drums being spaced from each other to permit the passage of gases of combustion therebetween, an enclosure about said drums provided with a flue at its rear end intermediate said rear drums, a plurality of banks of tubes connecting the front drum with the lower of the rear drums, a bank of tubes connecting the upper rear drum with said front drum, means for introducing feed water into said upper rear drum, a baffle extending along the bottom of the lowest bank of tubes from the bridge wall toward the front of said enclosure, a baffle on top of said lowest bank of tubes from the front to adjacent the rear end, and a baffle on top of the middle bank of tubes from said rear drum to adjacent the front end of said tubes to direct the heated gases over said tubes in a predetermined manner.

4. In a device of the kind described and in combination, a boiler having a front drum, a pair of rear drums at different elevations below said front drum, said rear drums being spaced from each other to permit the passage of gases of combustion therebetween, a plurality of banks of tubes directly connecting the front drum with the lower rear drum, a bank of tubes directly connecting the front drum with the upper portion of the upper rear drum, means for introducing feed water into the upper rear drum and baffles for directing the gases over said tubes and between said rear drums so that said gases contact with the top bank and the upper rear drum just prior to their discharge from the boiler.

5. In a device of the kind described and in combination, a boiler having a front drum, a pair of rear drums at different elevations below said front drum, said rear drums being spaced from each other to permit the passage of the hot gases of combustion therebetween, a plurality of banks of tubes directly connecting the front drum with the lower rear drum, a bank of tubes directly connecting the front drum with the upper portion of the upper rear drum, means for introducing feed water into said upper rear drum, an enclosure for said drums having a bridge wall disposed intermediate said front and rear drum, a baffle disposed along the lowermost bank of tubes and extending from said bridge wall to a point adjacent the front wall, a second baffle extending from the front drum to a point adjacent the lower rear drum, said second baffle being disposed intermediate said plurality of banks of tubes connecting said front drum with said lower rear drum, and a third baffle extending from the lower rear

drum to a point adjacent the front drum, said third baffle being disposed beneath said bank of tubes connecting the front drum with the upper rear drum.

5 6. In a device of the class described and in combination, a boiler having a pair of rear drums arranged in spaced vertical alignment, a front drum arranged in a horizontal plane above the rear drums and in a vertical 10 plane spaced from that of the rear drums, inclined tubes forming communication between said drums, a gas outlet disposed in a plane between said rear drums and means for directing the gases over said tubes in a predetermined manner.

7. In a device of the class described and in combination, a boiler having a pair of rear drums arranged in spaced vertical alignment, a front drum arranged in a horizontal plane 20 above the rear drums and in a vertical plane spaced from that of the rear drums, two series of tubes vertically spaced from each other and connecting said front drum with the lower of said rear drums, tubes connecting the upper 25 of said rear drums with said front drum, baffles for directing the gases over said tubes in a predetermined manner, one of said baffles being disposed between the two series of tubes communicating with the lower of said 30 rear drums, and a gas outlet disposed in a plane between said rear drums.

In testimony whereof, I have hereunto signed my name.

GEORGE LASKER.
